(57) **CLAIM**

I claim the ornamental design for a bollard cover, as shown and described.

DESCRIPTION

FIG. 1 is a front perspective view of one embodiment of a bollard cover comprising a new, original and ornamental design;

FIG. 2 is a top perspective view of the bollard cover shown in FIG. 1;

FIG. 3 is a front elevational view of the bollard cover shown in FIG. 1;

FIG. 4 is a rear elevational view of the bollard cover shown in FIG. 1;

FIG. 5 is a right side elevational view of the bollard cover shown in FIG. 1;

FIG. 6 is a left side elevational view of the bollard cover shown in FIG. 1;

FIG. 7 is a top view of the bollard cover shown in FIG. 1;

FIG. 8 is a bottom view of the bollard cover shown in FIG. 1;

FIG. 9 is a cross-sectional view of the bollard cover shown in FIG. 1, taken along line 9-9 in FIG. 3;

FIG. 10 is a cross-sectional view of the bollard cover shown in FIG. 1, taken along line 10-10 in FIG. 3;

FIG. 11 is a detail view of the bollard cover shown in FIG. 1, taken of the circled area in FIG. 9;

FIG. 12 is a front elevational view of a first panel of the bollard cover shown in FIG. 1;

FIG. 13 is a rear elevational view of the first panel of the bollard cover shown in FIG. 1;

FIG. 14 is a left elevational view of the first panel of the bollard cover shown in FIG. 1;

FIG. 15 is a right elevational view of the first panel of the bollard cover shown in FIG. 1;

FIG. 16 is a top elevational view of the first panel of the bollard cover shown in FIG. 1;

FIG. 17 is a bottom elevational view of the first panel of the bollard cover shown in FIG. 1;

FIG. 18 is a front elevational view of a second panel of the bollard cover shown in FIG. 1;

FIG. 19 is a rear elevational view of the second panel of the bollard cover shown in FIG. 1;

FIG. 20 is a left elevational view of the second panel of the bollard cover shown in FIG. 1;

FIG. 21 is a right elevational view of the second panel of the bollard cover shown in FIG. 1;

FIG. 22 is a top elevational view of the second panel of the bollard cover shown in FIG. 1;

FIG. 23 is a bottom elevational view of the second panel of the bollard cover shown in FIG. 1;

(Continued)

FIG. 24 is a partially cut-away front perspective view of the bollard cover shown in FIG. 1, in a first example use environment;
 FIG. 25 is a partially cut-away front perspective view of the bollard cover shown in FIG. 1, in a second example use environment;
 FIG. 26 is a front perspective view of another embodiment of a bollard cover comprising a new, original and ornamental design;
 FIG. 27 is a top perspective view of the bollard cover shown in FIG. 26;
 FIG. 28 is a front elevational view of the bollard cover shown in FIG. 26;
 FIG. 29 is a rear elevational view of the bollard cover shown in FIG. 26;
 FIG. 30 is a right side elevational view of the bollard cover shown in FIG. 26;
 FIG. 31 is a left side elevational view of the bollard cover shown in FIG. 26;
 FIG. 32 is a top view of the bollard cover shown in FIG. 26;
 FIG. 33 is a bottom view of the bollard cover shown in FIG. 26;
 FIG. 34 is a cross-sectional view of the bollard cover shown in FIG. 26, taken along line 34-34 in FIG. 28;
 FIG. 35 is a cross-sectional view of the bollard cover shown in FIG. 26, taken along line 35-35 in FIG. 28;
 FIG. 36 is a detail view of the bollard cover shown in FIG. 26, taken of the circled area in FIG. 34;
 FIG. 37 is a front elevational view of a first panel of the bollard cover shown in FIG. 26;
 FIG. 38 is a rear elevational view of the first panel of the bollard cover shown in FIG. 26;
 FIG. 39 is a left elevational view of the first panel of the bollard cover shown in FIG. 26;
 FIG. 40 is a right elevational view of the first panel of the bollard cover shown in FIG. 26;
 FIG. 41 is a top elevational view of the first panel of the bollard cover shown in FIG. 26;
 FIG. 42 is a bottom elevational view of the first panel of the bollard cover shown in FIG. 26;
 FIG. 43 is a front elevational view of a second panel of the bollard cover shown in FIG. 26;
 FIG. 44 is a rear elevational view of the second panel of the bollard cover shown in FIG. 26;

FIG. 45 is a left elevational view of the second panel of the bollard cover shown in FIG. 26;
 FIG. 46 is a right elevational view of the second panel of the bollard cover shown in FIG. 26;
 FIG. 47 is a top elevational view of the second panel of the bollard cover shown in FIG. 26;
 FIG. 48 is a bottom elevational view of the second panel of the bollard cover shown in FIG. 26;
 FIG. 49 is a partially cut-away front perspective view of the bollard cover shown in FIG. 26, in a first example use environment;
 FIG. 50 is a partially cut-away front perspective view of the bollard cover shown in FIG. 26, in a second example use environment; and,
 FIG. 51 is an isometric exploded view of the bollard cover shown in FIG. 26, in the second example use environment. The broken lines shown in FIGS. 24-25 and FIG. 49-51 illustrate environment and form no part of the claimed design. The dash dot lines shown in FIGS. 9, 11, 34, and 36 indicate the boundary of the enlarged views.
